UNITED STATES PATENT OFFICE

121,521

DESIGN FOR A SMOKER'S PIPE

Cornelius S. Nicoud, Chicago, Ill.

Application April 12, 1940, Serial No. 91,630

Term of patent 7 years

To all whom it may concern:

Be it known that I, Cornelius S. Nicoud, a citizen of the United States, residing at Chicago, in the county of Cook and State of Illinois, have invented a new, original and ornamental Design for a Smoker's Pipe, of which the following is a specification, reference being had to the accompanying drawing, forming a part thereof in which:

Fig. 1 is a plan view of the pipe showing my new design.

Fig. 2 is a side elevational view.

Fig. 3 is an inverted plan view.

Fig. 4 is an end elevational view thereof with the bowl member shown in the other views omitted.

I claim:

The ornamental design for a smoker's pipe, as shown and described.

CORNELIUS S. NICoud.
